MILK CARTON HOLDER

Nicholas R. Liberty, Columbus, Ohio

Application November 18, 1958, Serial No. 53,421

Term of patent 14 years

(Cl. D58—26)

FIG. 2

The rear of the holder not shown is plain.

I claim:

The ornamental design for a milk carton holder, substantially as shown and described.
